United States Patent Office

Des. 191,815
Patented Nov. 21, 1961

191,815

ALTAR CLOTH OR SIMILAR ARTICLE

Otto A. Scheurman, 502 Lincoln Ave., Ridgewood, N.J.

Filed Aug. 10, 1961, Ser. No. 66,276

Term of patent 7 years

(Cl. D92—1)

The figure is a plan view of an altar cloth embodying my new design.

The cloth is shown on a dark background to bring out the details of the design.

I claim:

The ornamental design for an altar cloth or similar article, as shown and described.
